UNITED STATES PATENT OFFICE.

BASIL SANER, OF WEST NEW YORK, NEW JERSEY.

EMBROIDERING-MACHINE.

1,078,881.

Specification of Letters Patent. Patented Nov. 18, 1913.

Application filed October 1, 1912. Serial No. 723,317.

To all whom it may concern:

Be it known that I, BASIL SANER, a citizen of the United States, and residing at West New York, in the county of Hudson and 5 State of New Jersey, have invented certain new and useful Improvements in Embroidering-Machines, of which the following is a specification, such as will enable those skilled in the art to which it appertains to 10 make and use the same.

This invention relates to embroidering machines, and particularly to what are known as Swiss and German embroidering machines, and the object thereof is to improve 15 a machine of this class by doing away with the shuttle and bobbin devices and the mechanism for operating the same, and substituting therefor a novel stitch forming mechanism whereby the operation of embroidering any design on a cloth or fabric may be performed with a single thread where 20 two have heretofore been employed, and whereby an improved lock-chain stitch formed which consists of a single thread 25 on one side of the cloth or fabric and a double thread on the opposite side of the cloth or fabric, and whereby both the construction and operation of the machine is cheapened and simplified and the operation 30 and results produced improved; and with this and other objects in view the invention consists in an embroidering machine of the class specified constructed and operating as hereinafter described and 35 claimed.

The invention is fully disclosed in the following specification of which the accompanying drawing forms a part, in which the separate parts of my invention are designated by suitable reference characters in 40 each of the views, and in which;—

Figure 1 is a transverse sectional view through an embroidering machine of the class specified, but showing only certain details of the machine as originally constructed and my improvements in connection therewith;—Fig. 2 a rear view of the construction shown in Fig. 1;—Fig. 2^a, a sectional detail of a part of the construction 45 shown in Fig. 1, and showing one of the loopers which I employ and its support and operating arm;—Fig. 3 a plan view of the construction shown in Fig. 2 with certain parts omitted;—Figs. 4, 5, 6, 7 and 8 detail 50 prospective views of the cloth plate of the

machine and showing one of the needles and one of the looping devices, and different steps in the operation of forming a stitch;—Fig. 9 a front view of a part of a cloth or fabric sheet and showing a line of stitches 60 produced by a single needle and a corresponding looper;—Fig. 10 a view similar to Fig. 9, but showing the reverse side of the cloth or fabric, and Fig. 11 a side view of a part of a finger bar. 65

In the accompanying drawing, I have shown only such parts of the original machine as are necessary to illustrate and describe the construction and operation of my improvement, and in Figs. 1, 2 and 3 of the 70 accompanying drawing, I have shown at *a* the shuttle bar of a machine of the class specified, or the bar in connection with which the ordinary shuttles have heretofore been mounted, and it will be understood that this bar is stationary and extends from one end of the machine to the other. I have also shown at *b* the presser finger bar which carries the presser fingers *b*² and the bar *b* has a slight rotary movement in opposite directions and extends the full length of the machine, and this bar with its fingers *b*² are the same as in the original machine, and in practice, a large number of the fingers *b*² are employed. I have also shown 80 at *c* the usual needle bar which also extends the full length of the machine, and is provided with the usual needle brackets *c*² having the usual needles *c*³, and the bar *c* has a forward and backward movement, and the needle brackets *c*² and needles *c*³ correspond in number with the presser fingers *b*². I have also shown at *d* the borer bar which extends the full length of the machine, and has a forward and backward movement, and 85 which is provided with the usual borers *d*² which are arranged in pairs in separate vertical planes, between the presser fingers *b*². I have also shown at *e* and *e*² the ordinary thread guide rods which extend the full 90 length of the machine and over and around which the threads *e*³ are passed, and it will be understood that a thread *e*³ is employed in connection with each of the needles *c*³, and the thread guide rods *e* and *e*² also have 95 a forward and backward movement, in the operation of the machine, in order to take up or regulate the slack or tension of the threads *e*³, and it will be understood that each of the threads *e*³ is wound on a bobbin 100 105 110

suitably supported at the front of the machine in the usual manner.

Supported at the back of the machine and at the rear of the shuttle bar a are a plurality of equally spaced bell cranks f having downwardly directed arms f^2 and laterally directed arms f^3 . The supports of these bell cranks are indicated at f^4 , in Fig. 2 only, but it will be understood that these bell cranks form a part of the old machine and are supported in the usual manner.

The laterally directed arms f^3 of the bell cranks f are forked, the separate members of said arms being shown at f^5 in Fig. 1, and mounted in the forked ends of said bell cranks are pins f^6 and mounted on the pins f^6 are links g having forked heads g^2 through which are passed pins g^3 , and mounted on the pins g^3 in the forked heads of the links g are bars g^4 .

In the original machine the parts a , b , c and d with their connections are all duplicated, one series of said parts being above the other, and the bars g^4 extend upwardly and are connected with the upper series of said parts so that the said series are operated simultaneously, and it will be understood that the bell cranks f and the parts f^4 , g and g^4 are all of the usual construction, and there is one of the bars g^4 employed in connection with each of the bell cranks f , and said bell cranks are operated by a horizontally reciprocating rod g^5 .

In the practice of my invention, I secure to the top of the shuttle bar a and transversely thereof a series of brackets h which correspond in number with the cranks f and are provided with raised, backwardly directed heads h^2 in which are mounted vertically arranged pins h^3 .

The inner ends of the pins g^3 are provided with heads h^4 in which the lower ends of the pins h^3 are secured, and secured to the upper ends of the pins h^3 is a bar i which extends the full length of the machine, and in the operation of the machine the pins g^3 and h^3 are given a vertical movement as is also the bar i .

The bar i is provided with a plurality of backwardly directed looper supporting arms i^2 which corresponds in number with the needles c^3 , and directly over the bar i is a looper operating bar j which also extends the full length of the machine, and in practice is given a longitudinal, intermittent, reciprocatory movement, and the bar j is provided with a plurality of forwardly directed looper operating arms j^2 which correspond in number with and operate in connection with the looper supporting arms i^2 .

The looper supporting arms i^2 and the looper operating arms j^2 are provided with heads i^3 and j^3 , as clearly shown in Figs. 1 and 2, and I have also provided a plu-

rality of loopers k which equal in number the arms i^2 and j^2 and which consist of cylindrical body portions k^2 which are passed downwardly through the heads i^3 and j^3 of the arms i^2 and j^2 and on the lower end portions of which are mounted collars k^3 which are secured thereto by pins k^4 , or in any other way, and the heads j^3 of the arms j^2 are secured to the body portions k^2 of the loopers k by pins k^5 . The top front portion of the loopers k are cut out to form longitudinal recesses k^6 at the tops of which are two upwardly directed fingers k^7 separated by deep recesses k^8 , and back of the fingers k^7 are shoulders k^9 on which the thread loops rest at one stage of the operation of forming my improved lock-chain stitch, this construction being clearly shown in Figs. 2² and 4 to 8 inclusive.

I also provide a cloth plate m which extends the full length of the machine and is secured to the brackets h in a vertical position corresponding with the position of the presser finger b^2 and between which and said fingers the cloth or fabric m^2 to be operated upon or embroidered is placed or supported, and made movable in the usual manner. The plate m is provided with a plurality of apertures m^3 which are arranged in horizontal and vertical rows and the apertures in the vertical rows are three in number, the top apertures being for the needles c^3 , the bottom apertures being for the borers d^3 . Secured to the back face of the cloth plate m between the upper rows of apertures m^3 are brackets m^4 in which is mounted a longitudinal intermittently reciprocating finger bar n provided with a plurality of pull fingers n^2 having lateral extensions or hook members n^3 and which correspond in number with the loopers k and needles c^3 , and operate in connection therewith as hereinafter described.

I have also shown at o the main drive shaft of the machine, and in the practice of my invention, I gear in connection therewith a horizontal cam shaft o^2 , this construction being clearly shown in Fig. 3, and this shaft is provided with two cams o^3 and o^4 and at one side of the cam shaft o^2 the frame work of the machine is provided with a bracket o^5 to which are pivoted two cam operated levers p and r . The cam lever p is provided with an antifriction roller p^2 in connection with which the cam o^4 operates, and the cam lever r is provided with an antifriction roller r^2 in connection with which the cam o^3 operates. Connected with the free end of the cam lever p is a link p^3 which is also connected with the corresponding end of the looper operating bar j and the connection of the link p^3 with both the lever p and bar j is a loose or universal connection, as shown at p^4 and p^5 .

The free end of the lever r is provided

with a link r^3 which is connected with the finger bar n , these connections being shown at r^4 , and the connection of the link p^3 with bar j at p^4 is made by means of a lateral hook-shaped extension formed on the end of said bar, as shown at p^6 in Fig. 3, and whereby said bar is given a longitudinal movement, and in the operation of the machine, this bar is also given a lateral movement by the arms j^2 which operate the loopers k .

The levers p and r are operated in one direction by the cams o^3 and o^4 and in the opposite direction by springs s and s^2 , and said springs serve to hold said levers in their outmost position, as will be readily understood.

It will be understood that the sheet m^2 of cloth or fabric to be embroidered is supported in a frame which extends the full length of the machine, and which is operated by a pentagraph device in the usual manner, said frame and pentagraph being not shown.

25 The upper ends of the presser fingers b^2 are provided with inwardly set parts b^3 and the upper edge portion of the plate m is provided with a correspondingly inwardly set longitudinal portion m^5 between which the cloth or fabric sheet m^2 is held and immediately below which the needles c^3 operate, and the object of this construction is to hold said sheet in proper position without interfering with the movement thereof.

35 The longitudinal movement of the bars j and n , in the operation of the machine, is an alternate movement, or in other words, when one of said bars moves in one direction the other moves in the opposite direction, and in the operation of the machine the needles c^3 are threaded in the usual manner, and the position of the cloth or fabric sheet m^2 adjusted as desired. In the first movement of the various parts of the machine, in beginning the process of embroidery, the needles c^3 and loopers k are thrown into the position shown in Fig. 4, which is the position assumed at the beginning of the formation of a stitch, at which

40 time the needles c^3 are at the limit of their projection through the cloth plate m , and the loopers are in their lowermost position caused by rocking the bell cranks f through the bar g , and the loopers are also slightly 45 rotated by the cam o^4 through the cam lever p , link p^3 and looper operating bar j . The second step in the formation of my improved lock-chain stitch is shown in Fig. 5, in which

50 a needle c^3 is shown slightly withdrawn 55 leaving a wide loop y in the thread c^3 , a looper k being shown turned to its limit of rotary movement to the left, and under one-half of the loop y . The third step is shown in Fig. 6, in which a looper k is raised, a finger k^7 projecting into the loop y and the

thread resting on the shoulders k^9 . The fourth step in the operation of forming my improved lock-chain stitch is shown in Fig. 7, in which a needle c^3 is withdrawn entirely leaving the loop y resting on the shoulders k^9 and a looper k raised and partially rotated to the right from its position shown in Fig. 6. The fifth and last step is shown in Fig. 7, in which a finger n^2 carried in the finger bar n is holding the loop y down below the path of travel of a needle c^3 . The needle c^3 is projected through the cloth plate m and through the recess k^8 in a looper k , which latter is shown entirely raised and turned to its limit of rotary movement to the right, and as the parts assume the position again, shown in Fig. 4, the loop y is drawn forward through the aperture m^3 over the needle and into the fabric, the result being shown in Figs. 9 and 10.

70 It will be understood that the borers or borer needles d^2 operate in the same manner as in other machines of this class, and in their operation pass through the corresponding apertures m^3 in the plate m .

75 While I have shown and described the preferred form of my improvement, it will be understood that my invention is not limited to the exact details of construction herein shown and described, and various changes therein and modifications thereof may be made, within the scope of the appended claims without departing from the spirit of my invention or sacrificing its advantages.

80 Having fully described my invention what I claim as new and desire to secure by Letters Patent is:

1. An embroidery machine provided with the usual thread needles, an apertured cloth plate through which said needles are movable, vertically movable and rotatable loopers secured adjacent to the side of said plate opposite said needles, and pulling devices mounted between said loopers and said plate and operating in connection with the needles and loopers to form embroidery stitches with one thread.

105 2. An embroidery machine provided with the usual thread needles, borer needles and presser fingers, an apertured cloth plate in connection with which the presser fingers operate, longitudinally reciprocating bars mounted adjacent to said cloth plate and on the side thereof opposite said needles, and loop former devices connected with said bars and operating in connection with the thread needles for forming embroidery stitches with one thread.

110 3. An embroidery machine provided with the usual thread needles, borer needles, and presser fingers, an apertured cloth plate supported adjacent to said fingers and in connection with which they operate, vertically movable loopers supported adjacent to the side of said plate opposite the thread needles

and having a vertical and rotary movement, and a finger bar mounted between said loopers and said plate and longitudinally movable and provided with fingers having lateral extensions.

4. In an embroidery machine, a longitudinally reciprocating finger bar provided with fingers having lateral extensions, and loopers supported adjacent to said bar and 10 having a rotary and vertical movement, said loopers being provided with vertical fingers

at the bottoms of which are shoulders between which are vertical recesses.

In testimony that I claim the foregoing as my invention I have signed my name in 15 presence of the subscribing witnesses this 28th day of September 1912.

BASIL SANER.
